UNITED STATES PATENT OFFICE.

GUSTAV A. BRACHHAUSEN, OF RAILWAY, NEW JERSEY.

DESIGN FOR A MUSIC-BOX BODY.

SPECIFICATION forming part of Design No. 27,059, dated May 18, 1897.

Application filed April 1, 1897. Serial No. 630,305. Term of patent 14 years.

To all whom it may concern:

Be it known that I, GUSTAV A. BRACHHAUSEN, a subject of the Emperor of Germany, residing at Rahway, Union county, 5 State of New Jersey, have invented and produced a new and original Design for Music-Box Bodies, of which the following is a specification, reference being had to the accompanying drawing, which forms part hereof, 10 and wherein the figure represents a perspective view of a music-box body embodying my invention.

The characteristic features of my design consist in a rectangular body portion which 15 is provided with panels on the sides and ends thereof and a base surrounded by a molding.

In the drawing, A represents a rectangular box which is provided with panels *a* on the sides and ends thereof. These panels may be divided by corner-moldings *b* and are 20 mounted upon a base *B*, which is surrounded by a molding *c*. The box may, if desired, be provided with feet *d*.

What I claim is—

The design for music-box bodies, substantially as shown and described. 25
